UNITED STATES PATENT OFFICE.

ROBERT NOBLETT, OF AUDENSHAW, NEAR MANCHESTER, ENGLAND.

APPARATUS FOR STRETCHING HIDES, SKINS, AND THE LIKE.

1,105,824.

Specification of Letters Patent.

Patented Aug. 4, 1914.

Application filed December 31, 1912. Serial No. 739,488.

To all whom it may concern:

Be it known that I, ROBERT NOBLETT, a subject of the King of Great Britain and Ireland, and resident of Audenshaw, near Manchester, England, have invented an Improved Stretching Board or Apparatus for Use Chiefly in Stretching Skins, Hides, and the like, of which the following is a specification.

This invention refers to the stretching and drying of skins or hides after being dyed or similarly treated, and its object is a construction of stretching board or apparatus whereby the skins or hides may be stretched more uniformly and to a greater extent than heretofore. At present the skins or hides are nailed to a board, the operator distending them as much as possible by hand as the nailing proceeds. Owing however to their irregular shapes, and owing also to the stretching being done by hand, the skins or hides are not always equally distended and the amount of stretch is not what it should be.

According to this invention the stretching board or apparatus, instead of being made with all parts fixed, is made with relatively fixed and relatively movable parts. These latter are adapted to be adjusted away from and toward the fixed parts, and preferably by such means as will afford a gradual and powerful force. To these movable parts are secured by their edges the skins or hides to be stretched, and when the parts are separated the skins or hides are stretched and held stretched in a manner which insures of an even distention of all parts of the skin and a degree of stretching greatly in excess of that obtainable by hand. Usually the relatively fixed part will be central between two movable parts, and one board will be designed to hold several skins.

Upon the accompanying drawings, Figure 1 illustrates a front elevation of a stretching board constructed according to the invention, and embodying one method of applying the invention. Fig. 1^a illustrates a similar view of a stretching board constructed according to the invention and embodying another method of applying the invention. Fig. 2 illustrates a plan of Fig. 1. Fig. 2^a illustrates a plan of Fig. 1^a. Figs. 3, 4 and 5 illustrate front elevations respectively of further examples of the invention.

Referring to Figs. 1 and 1^a, a', a² are the

two relatively movable or adjustable parts of the board, while b is the relatively fixed part which serves to connect the two horizontal members c', c². The two parts a', a² while free to move along the face of the members c', c² are held thereto by bolts d and lock nuts e, each part having slots a³ through which the bolts pass and each slot being surrounded by a metal facing a⁴. f', f² are two further parts which, as hereinafter described, may be either fixed or adjustable. To the fixed part b top and bottom is secured a bracket g wherein is mounted a spindle or rod h, the rod being free to rotate but incapable of moving endwise. At and near each end the rod is screw threaded and while the thread at one end is left handed the thread at the other end is right handed. To each of the movable parts a', a² top and bottom are secured brackets i, i and in one with each bracket is a tubular boss j. This boss, which virtually forms a nut, is screw-threaded internally to receive one of the screwed parts of the rod h, the screw thread of each boss agreeing with the thread of that part of the rod with which it engages. Upon each rod and lying between the forks of the bracket g is a hand wheel k by which the rod may be rotated to right or left. The upper longitudinal fixed member c' is supported at each end by fixed steel joists l, the ends of such upper member being reduced to form shoulders and the faces which bear against the joists being metal-faced to insure of the boards being readily moved along the joists. The several members (a'), (a²), (c'), (c²) are in the form of narrow boards, the members (c'), (c²) being what may be termed carrier boards. The parts f', f² are in the form of short sectional boards.

In proceeding to fix a dyed skin or hide to the board for the purpose of stretching and drying the same, the movable parts a', a² are caused to lie at their shortest distance apart, as shown. The skin or hide is then nailed or otherwise secured by its edge to the said movable parts and the fixed parts as shown by dotted lines, the neck part of the skin being preferably arranged lowermost, so that the skin will hang naturally downward and be easily manipulated.

When the skin or hide is fully secured to the board and ready to be stretched, the hand wheels k are each rotated in a direction which causes the parts a', a² to sepa-

rate, the screwed rods and bosses affording a very gradual distention of the skin or hide until it is fully stretched. The limit of stretch will be determined either by the operator, or by the slots a^3 . When fully distended the skin or hide is left to dry, which takes place in the usual way.

To remove the skin or hide after drying, the nails are removed, when it will be found that the skin or hide is considerably larger than when stretched by hand. To make ready for the next skin or hide the rods h, h are rotated in a direction which serves to cause the movable parts a', a^2 to again come to their normal position. To provide for the neck part of the skin or hide being stretched proportionately to the body part, the parts f', f^2 are made movable, but instead of moving with the parts a', a^2 as soon as these latter begin to separate, they move only after the said parts a', a^2 have completed a portion of their movement. For this purpose the parts a', a^2 are each provided with a slotted plate m which engages a fixed pin or stud n on the part f' or f^2 next to it, the stud being so placed relatively to the slot that not until the parts a', a^2 have done a portion of the stretching of the body part of the skin are the parts f', f^2 moved away from each other and then only by the plates engaging the studs. In this way the neck part of the skin is stretched proportionate to the body part. The parts f', f^2 will be held to the lower member c^2 by bolts o and lock nuts p and also to the fixed part b by dowels q , these latter being adapted to slide in dowel holes formed in the edges of the part b . The openings r between the parts a', a^2 and b are intended to insure of the operator always nailing the skins to the parts a', a^2 in about the same position. The spaces between part b and parts a', a^2 opposite the members c', c^2 may be filled in to afford a level surface.

In the arrangement shown in Figs. 2 and 2^a, a right and left handed screwed rod t is used which extends down behind the fixed part b of the board, and at points near each end is fitted with nuts t' . To each of these nuts are pivotally connected short links t'' which, in turn, are pivotally connected to rods t^3 working in guides u fixed to the members c', c^2 and connected to brackets u' on the parts a', a^2 . By the rotation of the screwed rod t , the nuts approach or recede from each other and thereby separate or draw together the parts a', a^2 of the board.

In Fig. 3 only the part a^2 is movable and the part b is dispensed with, the stretching being done by adjusting the movable part away from the fixed part a' . In this arrangement the screwed rods have a right (or left) hand thread only, and if desired one rod is rotated by an endless cord or chain from the other. For stretching the neck

part of the skin the parts f', f^2 will be movable in varying degrees, the part f^2 being connected to the part a^2 by a stud n' and slotted plate m^2 and the part f' being connected to the part f^2 by a stud n^2 and slotted plate m^2 so that after the part a^2 has partially stretched the body part of the skin or hide the part f^2 moves to partly stretch the neck part, after which the part f' moves to complete the stretching operation.

In Fig. 4, the fixed part b is arranged at say the end of the board, or at a point other than between the parts a', a^2 . The screwed rods v are each mounted in a bracket v' and held against endwise movement by collars v^2 . Each rod is fitted with a wheel w at one end and the right and left handed screwed parts respectively engage the like screwed bosses of brackets v^3, v^4 . The parts f', f^2 are either fixed or adjustable as in Fig. 1.

In Fig. 5 the improved board is shown with the parts a', a^2 and b arranged horizontally, instead of vertically, and the members c', c^2 arranged vertically instead of horizontally. The rods h and brackets g, i, i are arranged on the face of the board, but they may be arranged on the edges of the ends of the said parts as in Fig. 1. The two rods may also have pulleys and the rotation of one may serve, through the medium of an endless band or chain, to rotate the other. In this example of the invention the series of skins or hides to be stretched will usually require to be stretched all at the same time. The parts f', f^2 will be omitted and the spaces filled by further fixed parts extending from the member c' to the member c^2 .

What I claim is:—

1. A stretching apparatus for use in stretching hides, skins, and the like, comprising a pair of parallel carrier members suitably spaced apart, a central transverse member disposed at right angles thereto and having its ends rigidly secured to said members, a pair of similar transverse members arranged one on either side of said rigid member and having their ends slidably connected to said carrier members, a pair of short section members disposed on either side of said rigid transverse member between it and the adjacent slidably movable transverse member and parallel thereto, said section members being slidably connected with said movable transverse members and with said carrier members, and means for causing said movable transverse members to move along said carrier members, away from said rigidly secured transverse member, substantially as described.

2. In a stretching apparatus for use in stretching hides, skins, and the like, a frame comprising a pair of parallel carrier members suitably spaced apart, a transverse member connecting said members at their

central point and having its ends rigidly secured thereto, a pair of movable transverse members arranged on either side of said rigid member and having their ends slidably connected with said carrier members, short section members interposed between said rigid, transverse member and said movable transverse member and parallel thereto, and having their ends and sides slidably connected with said carrier members and said movable transverse members, respectively, means for moving said movable transverse members in opposite directions and

for moving said section members after said transverse members have been moved a predetermined distance, and means for limiting the movements of said transverse and said section members, substantially as described.

In witness whereof I have hereunto set my hand in the presence of two witnesses.

ROBERT NOBLETT.
